TROUSER BELT

Daniel J. Schaffner, Chicago, Ill.

Application October 21, 1936, Serial No. 106,861

8 Claims. (Cl. 24—248)

My invention relates to belts as employed for trousers and other garments, and my main object is to provide a relatively short belt which extends only partially around the trousers, yet fulfills the necessary function of supporting them in the proper place.

A further object of the invention is to procure comfort for the wearer by the use of the short belt with means to secure the necessary tension without applying pressure to the entire waist line.

A still further object of the invention is to provide a belt of the above description which engages the trouser top without requiring the same to carry fasteners, buttons, loops or other attaching means.

Another object of the invention is to provide the ends of the novel belt with a neat and sturdy clamping device for the trouser top, such clamping device causing no injury to or wrinkling of the same.

An additional object of the invention is to provide the clamping elements of the novel belt with means for easily straddling the top portion of the trousers, whereby to facilitate the application or removal of the belt.

A significant object of the invention is to form the terminal clamps for the novel belt with frontal shields or plates which fully conceal the working parts of the clamps and are capable of ornamentation like conventional belt buckles or ornaments.

An important object of the invention is to construct the clamps carried by the belt of few and simple parts, whereby to enable them to be produced at low cost.

With the above objects in view and any others that may suggest themselves from the specification and claims to follow, a better understanding of the invention may be had by reference to the accompanying drawing, in which—

Fig. 1 is a perspective view showing the application of the novel belt to a trouser top;

Fig. 2 is an enlarged front elevation of a clamp carried by the left-hand end of the belt and in the disengaged position;

Fig. 3 is a rear elevation of the clamp in Fig. 2 in the engaged position;

Fig. 4 is a top plan view of Fig. 2, showing the clamp applied; and

Fig. 5 is a view similar to Fig. 4, partly in section, showing the clamp in the engaged position.

Referring specifically to the drawing, 10 denotes the novel belt which is of a gauge or design in keeping with conventional styles, but is only about 8 or 10 inches long. It is my intention to equip this belt with clamps at the ends for application to the trouser top, so that the latter will be drawn into engagement with the body of the wearer quite as effectively as by a full-length belt.

In accordance with the foregoing, I provide a pair of clamps for the belt which are the same in general construction and function, but are symmetrically reversed when positioned at the ends of the belt. Thus, the left hand clamp is 10 clearly shown in Fig. 3, and it is seen that it is fundamentally in the form of a yoke composed of a frontal plate 11, a top bend 12 and a rear plate 13. The yoke is pressed or stamped from sheet metal of sufficient thickness to make it strong 15 and rigid, additional stiffness being imparted to the frontal plate 11 by forming the same transversely arcuate and with side and bottom bends 14 and 15, respectively. Also, the top bend 12 may be domed somewhat, as shown, to render 20 it rigid. With the bends 12, 14 and 15 joined in continuous formation when the plate 11 is pressed, it becomes proof to bending, separating or distorting influences.

The top and bottom bends 12 and 15 are perforated at the rear as indicated at 12a and 15a to form hinge ears for the terminal studs 16a of a clinch plate 16, which tapers in one direction from the pivots, as indicated at 16b, to form a curved hook 16c, and terminates shortly in the 30 other direction from the pivots with a series of hinge ears 16d. One side edge of an operative plate 17 is perforated at 17a for pivotal engagement by the hinge ears 16d, such plate occurring immediately behind the frontal plate 11. 35 The other side portion of the plate 17 has a long vertical slot 17b for the passage of the looped corresponding end 10a of the belt 10 to secure the same to the plate 17. The bar 17c adjoining the outer side of the slot 17 is of 40 doubled construction for strength, and is formed with rounded edges in order not to cut the belt when the latter is under tension.

When the parts of the clamp are positioned as in Figs. 2 and 4, the plate 17 is nestled in the hollow of the frontal plate 11 with the clinch plate 16 close to it on the other side. The clinch plate 16 is now amply spaced from the rear plate 13 to permit the clamp to straddle and fully receive the top 18 of the trouser as shown, the hook 16c of the clinch plate clearing the same.

On the other hand, when the operative plate 17 is drawn outwardly, as by the pull or tension of the belt, the clinch plate 16 is caused to swing inwardly on the pivots 16a and advance the hook 55

- 16a into engagement with the cloth of the trouser top. While the rear plate 13 generally forms a backing for the said cloth, the plate is formed with a triangular opening 13a as a clearance for the advance of the hook 16a in a manner to deform and confine the clinched material in the opening, causing the cloth to assume an S-course through the clamp. The inner side of the plate opening 13a is formed with rounded lugs 13c immediately alongside the course of the hook 16a, these confining the clinched cloth for a tighter grip by the hook. These formations not only firmly secure the cloth in the clamp, but take up a portion of the cloth in a lateral direction by virtue of the S-course taken by the cloth through the clamp. Thus, with two of the clamps terminally of the belt and engaged by the inward pull of the belt as described, the effect is to draw the trouser top close about the waist.
- 20 The belt is preferably mounted with one clamp at a time. Thus, with one clamp mounted and held by one hand, the other draws on the belt to cause the clamp to grip, and slides along the belt to take hold of and mount the other clamp, while the first hand pulls the trouser top adjacent such other clamp toward the center to permit that clamp to take hold as far out as possible. Now the tension of the belt, plus the wearer's abdominal pressure, maintains the belt sufficiently tense to keep the clamps engaged.
- 25 To supplement the clinch of the hook 16a on the trouser cloth against the bar 13b, the inner side thereof is extended with ridge-like lugs 13d, which serve during the clamping operation to anchor the cloth passing along the clinch plate. Thus, the cloth is not only clinched in the S-formation, but positively anchored by the hook 16a and the lugs 13c and 13d, although these parts are not sharp or angular and cannot therefore cut or tear the cloth. The plate 13 is slightly spread toward the bottom from the frontal plate 11 to facilitate mounting the clamp over the trouser top; and such plate 13 is also tapered downwardly at 13e and formed with 30 rearwardly flared points 13f and 13g at the side and bottom for the same purpose.
- 35 It is thus seen that a belt of the short type is had whose clamps can be readily mounted to straddle the trouser top because of their yoke-like form. No particular attention is required in the mounting of the belt, except that the end portions of the belt must each be held to its clamp in order to keep the operative plate 17 in and the clinch plate hook out of the way of 40 the cloth. The application of the belt becomes familiar after a few trials, and the hands of the wearer become accustomed to its manipulation without any attention or concern.
- 45 It is significant that the only part visible in either belt clamp is the frontal plate 11. The rear plate 13 is of course behind the trouser cloth; and the slotted portion of the operative plate 17, while extended from the side of the frontal plate, is almost entirely covered by the belt loop, and is 50 ordinarily invisible. Thus, only the belt is seen when a jacket is worn in partly open position; and, when the jacket is open wide or not worn, the terminal plates are also seen, suggesting buckles or ornaments. While the trouser top is 55 deformed or gathered where engaged by the clamps, the deformations do not extend below or aside from the same, so that the material is not visibly gathered or wrinkled. The plates may be made with initials, scrolls or other decorative effects, to form an attractive trim for the belt.
- 60
- 65
- 70
- 75

The latter thus constitutes an article of economy, by employing only a fraction of the customary belt material; an article of comfort by relieving the greater portion of the wearer's waist from undue and constricting pressure; an article of efficiency by being simply made, easily applied and firmly effective; and an article of good appearance by being neat, ornamentally versatile and devoid of mechanical or unsightly effects.

While I have illustrated and described the invention along specific lines, the same is clearly susceptible of minor changes and refinements, and I consider all such changes and refinements as coming within the scope and spirit of the appended claims.

I claim:

1. A clamp for a garment top comprising, a yoke adapted to surmount the latter and comprising front and rear yoke arms connected by a top bend, a rearward bottom bend of the frontal yoke arm opposite the top bend thereof, and means pivoted in said bends to swing relative to the rear yoke arm and clasp the garment top thereto, an extension of said means beyond the pivot, and a member linked to the extension and operable to swing said means.

2. A clamp for a garment top comprising, a yoke adapted to surmount the latter and comprising front and rear yoke arms connected by a top bend, a rearward bottom bend of the frontal yoke arm opposite the top bend thereof, and means pivoted in said bends to swing relative to the rear yoke arm and clasp the garment top thereto, said frontal arm being broad to serve as a frontal plate, said means comprising a securing plate substantially parallel to the frontal plate when in the normal position, an extension of the securing plate beyond the pivot, and an operative plate linked to the extension and extending in return direction from the point of linkage between the securing plate and the frontal plate, the movement of the operative plate in said direction procuring the swing of the securing plate.

3. A clamp for a garment top comprising, a yoke formed from frontal and rear plates joined by a top bend which surmounts the garment top, a rearward bottom bend of the frontal plate opposite the top bend thereof, and a plate pivoted between said bends and extended with a hook, the plate being adapted to be positioned on the frontal side of the garment top and swingable towards and away from said rear plate, and means operative to swing said hook toward said rear plate and clinch said garment top therebetween.

4. The structure of claim 3, the rear plate having an opening defining a bar, and the hook closing about the latter during the clinching action to impart an S-formation to the garment top material and lock the latter in the clamp.

5. The structure of claim 3, the rear plate having an opening defining a bar, and spaced lugs extended along the latter into the opening, and the hook being tapered to press the garment top material against the lugs during the clinching action of the hook to lock the material from slippage.

6. The structure of claim 3, the rear plate having an opening defining a bar, and ridges extended along the latter toward the hollow of the hook, such ridges anchoring the garment top material against slippage during the clinching action of the hook.

7. In a belt adapted to be secured to a garment top, a clamp carried by one end portion of said belt and adapted to secure said belt to said garment, said clamp comprising a yoke adapted to straddle said garment top, means pivotally carried by said yoke, means carried by said belt end portion and pivotally connected to said first means, said first means being movable upon the tensioning of said

belt to engage said garment top and clasp the same to a portion of said yoke.

8. The structure of claim 7, said portion of said yoke and said first means being formed to inter-
engage and clasp said garment top into an S-for- 5
mation therebetween.

DANIEL J. SCHAFFNER.
